[57] CLAIM

The ornamental design for a stuffed animal type pony head and frame for mounting on a stroller or the like with reins for rider to hold, as shown and described.

DESCRIPTION

FIG. 1 is a left side perspective view of a stuffed animal type pony head and frame for mounting on a stroller or the like with reins for rider to hold showing my new design, the broken lines are for illustrative purposes only and form no part of the claimed design;

FIG. 2 is a right side perspective view thereof, a portion of the side frame is shown broken away for convenience of illustration; and,

FIG. 3 is a fragmentary portion of the reins on a greatly enlarged scale.
